(57) **CLAIM**

The ornamental design for a massage belt as shown and described.

DESCRIPTION

1.1 : Perspective

1.2 : Perspective

1.3 : Front

1.4 : Back

1.5 : Left

1.6 : Right

1.7 : Top

1.8 : Bottom

1.9 is an enlarged top view of the massage belt.

1.10 is an enlarged bottom view of the massage belt.

1.11 is a cross-sectional view taken from cut-line with arrows labeled **11-11** in reproduction **1.4**.

1.12 is an enlarged perspective view taken from detail **12** in reproduction **1.1**.

1.13 is an enlarged perspective view taken from detail **13** in reproduction **1.1**.

1.14 is an enlarged perspective view taken from detail **14** in reproduction **1.2**.

1.15 is an enlarged perspective view taken from detail **15** in reproduction **1.2**.

(Continued)

1.16 is an enlarged perspective view taken from detail 16 in reproduction 1.2.

1.17 is an enlarged back view taken from detail 17 in reproduction 1.4.

1.18 is an enlarged right view taken from detail 18 in reproduction 1.6.

1.19 is an enlarged cross-sectional view taken from detail 19 in reproduction 1.11.

The evenly spaced broken lines in the depict portions of the massage belt that form no part of the claimed design. The dot-dash broken encircling the areas of enlargement forms no part of the claimed design.
